UNITED STATES PATENT OFFICE.

JAMES PAUL GRIFFITHS, OF DURBAN, SOUTH AFRICA.

CODING AND DECODING DEVICE.

1,389,559.

Specification of Letters Patent. Patented Aug. 30, 1921.

Application filed March 19, 1921. Serial No. 453,744.

To all whom it may concern:

Be it known that I, JAMES PAUL GRIFFITHS, a subject of the King of Great Britain, residing in Durban, South Africa, have 5 invented certain new and useful Improvements in a Coding and Decoding Device, (for which I have filed an application in Great Britain dated December 24, 1919, Serial No. 32,418), of which the following is a 10 specification.

The invention relates to a coding and decoding device in which according to the invention the characters are arranged in two rows, and two hands adjustably set to indicate at the same time, respectively, a character of each row at any required spacing apart are adapted to be moved together over the rows. The two rows can be relatively displaced and the order of blocks marked 15 with the characters can be changed as required in each row.

In a preferred form the device comprises a small portable and easily handled mechanism, in the form of, and approximately of 20 the usual dimensions of, a watch, on the front of which there are two hands which can be set at any required angular position apart and which can be readily placed opposite to numerals and letters arranged in 25 two concentric rings. When one hand is set to any numeral or letter of one ring the other hand points to the corresponding letter or numeral of the code.

By changing the angular spacing of the 30 hands a large number of different codes can be quickly obtained. One of the concentric rings can be rotated relatively to the other ring and arrangements are also provided by which the order of any of the letters or numerals in the two rings can be altered, so that a practically unlimited 35 number of different codes can be readily formed and the messages rapidly decoded.

Each correspondent is provided with a 40 similar instrument.

The accompanying drawing represents an example of a coding device according to the invention.

Figure 1 is a section and Fig. 2 a plan 45 with parts of the cover removed. Figs. 3 and 4 are sections, respectively, on the lines III-III and IV-IV of Fig. 1.

1 is the circular case of the instrument, 50 2 a metallic bezel, 3 a glass cover, 4 an annular plate secured to the case, 5 a central disk, the lower flange 6 of which lies in the

same horizontal plane as the plate 4. Numbered or lettered blocks 7 are arranged in two concentric rows in partitioned spaces 8 and 9 formed in the plate 4 and disk 5 by 55 radial ribs 10 and 11. The blocks 7 are also slightly wedge shaped both in plan as shown in Fig. 2 and in elevation as shown in Figs. 3 and 4, so as to be held securely when slipped into their appropriate places. The 60 blocks of the outer row rest against a circular rib or flange 12 and the blocks of the inner row against the vertical flange 13 of the inner disk 5. Circular channels 14 and 15 are provided in the plate 4 in which any 65 blocks can be temporarily placed when it is desired to alter the order of the blocks in either row.

In order to prevent any possible displacement of the blocks after they have been 70 placed in position, a ring 16 is provided with upturned flanges 17 adapted to bear, when slightly lifted by screws 18, against the bottom surfaces of the blocks. Three screws 18 are threaded in the example shown into 75 bosses provided in the base of the case.

The disk 5 can be rotated by means of a toothed rack 19 adapted to engage with a pinion 20 when a spindle 21 to which the pinion is secured is pulled against the pressure of a spring 22 toward the right. The spindle 21 is rotated by means of a knurled knob 23. In its normal position the knob 23 serves to rotate a pair of bevel wheels 24 and 25 and with them indicating hands 26 80 and 27 of which the longer hand 26 points to a block on the outer row 9 and the shorter hand 27 to a corresponding block on the inner row 8.

A bracket 28 secured to the case supports 85 the spindle 29 to which the indicating hands are attached. The spindle 21 is supported in a bearing 30 also secured to the case. The bevel wheel 25 and with it the hands 26 and 27 are held in the positions set by a detent 90 31, which slides outward to release the hands against the retaining pressure of a spring 32 when one arm 33 of a small pivoted lever 34 is pressed inward. The detent and its releasing means can be placed in any convenient 95 position and are shown in Fig. 2 near to the knob 23.

In order that the angular distance apart of the hands may be readily altered, in the example shown the spindle 29 is formed with a 100 square cross section on which the correspondingly formed end of the hand 27 fits; the 105

hand 26 fits over a circular portion of the spindle 29 and is locked by a nut 35.

Having thus described the nature of the said invention and the best means I know of carrying the same into practical effect, I claim:

1. A coding and decoding device comprising in combination a circular case, an annular plate secured within said case and having a row of partitioned spaces, a central disk, having a row of partitioned spaces arranged concentrically with the spaces in said plate, character bearing blocks fitting in said spaces, said plate having a circular channel surrounding each row of partitioned spaces into which channels any of said blocks may be slid temporarily for the purpose of changing the ordinary arrangement of the blocks, means for preventing displacement of said blocks, a spindle and supports therefor mounted in said case, indicating pointers secured to said spindle, means for moving said pointers simultaneously over said blocks and means for altering the angular distance apart of said pointers.

2. A coding and decoding device comprising in combination a circular case, an annular plate secured within said case and having a row of partitioned spaces, a central disk, having a row of partitioned spaces concentric with the row of spaces in said disk, character bearing blocks fitting in said spaces, a ring located below said partitioned spaces and having upturned flanges adapted to bear against the bottoms of said blocks, screws threaded into the base of said case and engaging with said ring, a spindle and supports therefor mounted in said case, indicating pointers secured to said spindle, means for moving said pointers simultaneously over said blocks and means for altering the angular distance apart of said pointers.

3. A coding and decoding device comprising

ing in combination a circular case, an annular plate secured within said case and having a row of partitioned spaces, a central disk, having a row of partitioned spaces concentric with the row of spaces in said plate, character bearing blocks fitting in said spaces, a spindle and supports therefor mounted in said case, indicating pointers secured to said spindle, means for moving said pointers simultaneously over said blocks, means for altering the angular distance apart of said pointers and means for rotating said central disk.

4. A coding and decoding device comprising in combination a circular case, an annular plate secured within said case, a central spindle mounted in said case, a central disk, said plate and said disk having complementary concentric rows of partitioned spaces, character bearing blocks fitting in said spaces, a rod mounted in said case, means external to said case for rotating said rod, a pinion on said rod, and a toothed wheel on said central spindle engaging with said pinion.

5. A coding and decoding device comprising in combination a circular case, an annular plate secured within said case, a central spindle mounted in said case, a central disk, said plate and said disk having complementary concentric rows of partitioned spaces, character bearing blocks fitting in said spaces, a rod mounted in said case so as to slide axially, means external to said case for rotating said rod, a pinion on said rod, a toothed wheel on said central spindle engaging with said pinion in one axial position of the rod, a rack on said central disk, a second pinion on said rod engaging in another axial position of the rod with said rack.

In testimony whereof I have signed my name to this specification.

JAMES PAUL GRIFFITHS.
